MULTI-POSITION RECLINING CHAIR

Ernest S. Rosmarin, Roslyn, Long Island, N.Y., assignor,
by mesne assignments, to Super Sagless Spring Corp.,
Amsterdam, N.Y., a corporation of New York
Filed Jan. 10, 1963, Ser. No. 250,986
20 Claims. (Cl. 297—85)

This invention relates to reclining chairs of the type which include a separate back-rest, a separate seat and a separate leg-rest that are movable with respect to each other in response to pressure applied to the back-rest, for placing said body-supporting parts of the chair in a multiplicity of relative positions.

An object of the present invention is to provide a chair of the indicated type with improved means for actuating the various body-supporting parts of the chair to place said parts in a multiplicity of positions.

Another object is to provide a reclining chair with improved means for locking parts of the linkage actuating mechanism of the chair during movement of the body-supporting parts of the chair from one position to another.

A further object is generally to provide an improved operating linkage mechanism for a multi-position reclining chair.

The above and other objects, features and advantages of the present invention will be more fully understood from the following description of the invention considered in connection with the accompanying drawings which are illustrative of an embodiment of the invention and not in limitation thereof.

In the drawings:

FIG. 1 is a side elevational view of a reclining chair in accordance with the present invention, illustrating the body-supporting parts of the chair in an upright or sitting position;

FIG. 2 is a side elevational view of the chair of FIG. 1, illustrating the body-supporting parts of the chair in a reclined position, such as might be suitable for television viewing;

FIG. 3 is a side elevational view of the chair of FIG. 1, illustrating the body-supporting parts of the chair in a lounging position;

FIG. 4 is a side elevational view of the chair of FIG. 1, illustrating the body-supporting parts of the chair in a sleeping position;

FIG. 5 is a top plan view, with parts broken away, of the operating linkage mechanism of the chair, showing the parts thereof in an expanded condition for purposes of illustration;

FIG. 6 is a side elevational view of part of the linkage mechanism of the chair, illustrating a modification thereof; and

FIG. 7 is a side elevational view of part of the linkage mechanism of the chair, and illustrates another modification thereof.

Referring now to the drawings in detail, the reclining chair 10 comprises a frame 12 supported on legs 14. A support plate 16 is suitably secured to each side of frame 12 and supports the parts of the operating linkage mechanism of the chair, which is provided at each side of the chair, as will be more clearly understood hereinafter. The body-supporting means of the chair includes a separate and movable back-rest 18, a separate and movable seat 20 which can be provided with a cushion 22, and a separate and movable leg-rest 24.

The back-rest 18, seat 22, and leg-rest 24 are operatively connected to each other through an operating linkage mechanism, generally designated by the reference numeral 26, so that in response to pressure on the back-rest 18 as,

2

for example, by a person pushing his back against the back-rest to actuate the linkage mechanism, the body-supporting parts of the chair move into the successive positions illustrated by FIGS. 1 to 4, respectively. FIG.

5 illustrates the upright position of the chair; FIG. 2 illustrates the partial reclining or TV viewing position of the chair; FIG. 3 illustrates the full reclining or lounging position of the chair and FIG. 4 illustrates the sleeping position of the chair. The body-supporting parts of the chair are moved back to the upright position of the chair, illustrated by FIG. 1, from the sleeping position of the chair, illustrated by FIG. 4, by the application of pressure on seat 20, as, for example, by the sitter applying pressure against the seat through his buttocks.

15 Back-rest 18 is fixedly connected to a link 28 which has its rearward end pivotally connected at 30 to the upper end of a link 32 that is connected at its lower end to a pivot 34 which is fixedly connected to plate 16. Seat 20 is fixedly connected to a link 36 which is pivotally connected at its rearward end, at 38, to the forward end of link 28, and is pivotally connected at its forward end, at 40, at the upper end of a link 42. Near pivot 38, the upper end of a link 44 is pivotally connected at 46 to link 36 and the lower end of link 44 is pivotally connected at 48 to the forward end of a bell-crank 50 which is pivotally connected at 52 to plate 16. Near the forward pivot end 40 of link 36, the upper end of a link 54 is pivotally connected at 56 to link 36 and intermediate its length, link 54 is pivotally connected at 58 to the forward end 20 of another bell-crank 60 which is pivotally connected at 62 to plate 16. The lower end of link 54 is pivotally connected at 64 to the rearward end of a link 66 whose forward end is pivotally connected at 68 to link 42, at a position intermediate its length.

25 Links 54 and 66 operate leg-rest 24 in response to movement of link 36. More particularly, the upper end of a link 70 is pivotally connected at 72 to link 36 at a position between pivots 40 and 56. The lower end of link 70 is pivotally connected at 74 to the lower end of link 76 and the upper end of the latter is pivotally connected at 78 to the upper end of a support 79 on which leg-rest 24 is mounted. Links 42 and 76 are pivotally interconnected at 80 at a position near the lower ends of the links. The lower end of link 42 is pivotally connected at 82 to the lower end of a link 84 which is pivotally connected at its upper end, at 86, to leg-rest support 79, at a position above the lower end thereof.

30 It is to be observed from the above described operating interconnection of the back-rest 18, seat 20 and leg-rest 24, that pressure applied against the back-rest causes the latter to rotate rearwardly and downwardly on link 32 about fixed pivot 34, while seat 20, which is connected to link 36, rotates rearwardly on links 54 and 44, about pivots 58 and 48, respectively. At the same time, foot-rest 24 moves forwardly and upwardly about pivots 72 and 40 in response to forward movement of links 54 and 66. The foregoing movements continue until stud 88, which is secured to links 36 and extends from the side thereof, engages the forward edge of link 44, as shown in FIG. 2, at which time the body-supporting parts 18, 20 and 24 of the chair are in a reclining position which is especially suitable for television viewing. Links 28, 32 and 36 comprise first operating linkage means or the operating means for the back-rest and seat for movement thereof from the first position to the second position of the chair.

35 Additional pressure on back-rest 18 causes bell-cranks 60 and 50 to rotate in a clockwise direction, as viewed in FIG. 2, about their fixed pivots 62 and 52, respectively,

thereby raising seat 20 and moving back-rest 18 in a rearward and downward direction into the positions shown in FIG. 3, which is the lounging position of the chair. For releasably holding the different parts of the chair in their lounging positions, a link 90 is provided which is pivotally connected at its rearward end, at 92, to the rear lower end of bell-crank 50, and the forward end of the link is pivotally connected at 94 to the rearward end of bell-crank 60. A lever 96 is pivotally connected at its forward end to a fixed pivot 98 which is mounted on plate 16. The rearward end of lever 96 carries a stud 100 which is biased, by a torsion spring 102, into sliding engagement with the upper edge of link 90 which is provided with a wedge-shaped slot 104. The movements of the parts of the chair continue from their respective positions shown in FIG. 2 until stud 100 moves into slot 104, at which time the chair is in its lounging position as illustrated by FIG. 3.

Further pressure on back-rest 18 causes stud 100 to be cammed out of slot 104, thereby permitting further rotation of bell-cranks 60 and 50. Rotation of the bell-cranks continues until the lower edge of bell-crank 60 engages stop-stud 106 which extends from the side of plate 16, at which time the parts of the chair are in their sleeping position as shown in FIG. 4.

The parts of the chair are returned to their upright position by the user sitting up in the chair whereby the pressure against seat 20 automatically causes reverse movement of the parts into the positions illustrated by FIG. 1. A stop-stud 108 is provided and extends from the side of plate 16 in the path of movement of the lower edge of bell-crank 60 for engaging the latter in the upright position of the chair and thereby prevents further movement of the parts of the chair after they are in their proper positions corresponding to said upright position, as illustrated by FIG. 1.

Means is provided to prevent rotation of bell-cranks 60 and 50 which, with links 44, 54 and 90 comprise second operating linkage means of the actuating means of the back-rest and seat for movement thereof into said third and fourth positions, during the movements of the parts of the linkage operating mechanism 26 as the chair is moved through a first phase of movement from an upright position, illustrated by FIG. 1, to a partially reclining or TV viewing position, illustrated by FIG. 2. To this end there is provided a sequencing mechanism 110. The sequencing mechanism 110 comprises a sequence member 112, which is in the form of a plate that has an upper stop edge 114. Member 112 is pivotally mounted at its lower forward corner, at 116, to the forward end of crank 50. A roller 118 extends from the side of the sequence member, at its rear upper corner, and is biased by a torsion spring 120 in a direction which causes stop edge 114 (FIG. 1) to engage a stop-stud or keeper 122 that extends from the side of plate 16.

During the rearward movement of link 44 about its pivot 48, while the linkage mechanism 26 is being actuated from the upright position of the chair to the reclining position of the chair, as illustrated by FIGS. 1 and 2, respectively, the rearward edge of link 44 engages roller 118 and thereby causes member 112 to rotate clockwise, as viewed in FIG. 1, about its pivot 116. However, stop edge 114 still remains in engagement with stop-stud 122, thereby preventing rotation of the bell-cranks. As the linkage mechanism moves into its position corresponding to the reclining position of the chair, member 112 has rotated a sufficient amount, as illustrated by FIG. 2, so that edge 114 is no longer in engagement with stop-stud 122, and the bell-cranks are free to rotate upon the application of further pressure against back-rest 18 for moving the chair into its lounging position.

As illustrated by FIG. 6, other means can be provided for locating the lounging position of the chair in lieu of the spring-biased lever 96 and slot 104 in link 90, and which also eliminates stop-stud 106 for the sleeping posi-

tion of the chair. More particularly a slotted link 124 is provided which is slidably mounted on studs 126 and 128 that extend from the side of plate 16 through slot 130 of the link. A helical tension spring 132 has its rearward end fixed to a pin 134 which extends from the side of plate 16 and the forward end of the spring is fixed to a pin 136 which extends from the side of link 124, at the rear end thereof. The spring normally biases the link into the position shown in FIG. 6, with stud 126 in engagement with the forward end of the slot.

As link 60', which is the same as link 60 but which has been modified to provide a link engaging edge 138, moves from its position corresponding to the reclining position of the chair, illustrated in solid lines in FIG. 6, to its position corresponding to the lounging position of the chair, illustrated by dashed lines in FIG. 6, edge 138 of link 60' engages the rearward end of link 124 to stop the movement of the operating linkage mechanism 26 as it moves into position corresponding to the lounging position of the chair. Additional pressure on back-rest 18 to move the chair into its sleeping position, causes sliding movement of link 124, due to the forward movement of link 60', until the rearward end of slot 130 engages stud 128 to stop further movement of the parts of the chair after they are in the sleeping position of the chair. It is to be noted that spring 132 provides a counter-balancing force as the chair is moved from its lounging position to its sleeping position and this counter-balancing force assists in the return of the chair from its sleeping position to its lounging position.

If desired or required, it is within the scope of this invention to eliminate the fourth or sleeping position of the chair. This may be accomplished, as illustrated by FIG. 7, by eliminating lever 96, spring 102 and slot 104 in link 90, and the modification illustrated by FIG. 6, and moving stop-stud 106 rearwardly, so that crank 60 engages said stop-stud when the crank is in its position corresponding to the lounging position of the chair.

As is apparent, to return the chair from the fourth or sleeping position or from the third or lounging position illustrated by FIGS. 3 and 4, respectively, to its upright position illustrated by FIG. 1, it is not necessary to go back through the other positions. The chair may be returned directly to its upright position by applying pressure directly to leg-rest 24 to collapse the leg-rest operating linkage mechanism into the position illustrated by FIG. 1, wherein sequence member 112 is positioned above stop-stud 122 with its cam edge 114a also above the stud. Downward and direct return movement of the chair seat into the position illustrated by FIG. 1 causes stud 122 to engage cam edge 114a and rotate sequence member 112 clockwise as viewed in FIG. 1, permitting cam edge 114 to move under stud 122 and snap back into its normally locked position illustrated by FIG. 1.

While I have shown and described the preferred embodiment of the invention, it will be understood that the invention may be embodied otherwise than as herein specifically illustrated or described, and that certain changes in the form and arrangement of parts and in the specific manner of practicing the invention may be made without departing from the underlying ideas or principle of the invention within the scope of the appended claims.

I claim:

1. A reclining chair, comprising support means, a separate and movable back-rest and a separate and movable seat, operating means pivotally connected to said support means and interconnecting said back-rest and said seat, for moving the latter from a first position to a second position in response to movement of said back-rest from a corresponding first position to a corresponding second position, actuating means operatively connected to said operating means for moving said seat from said second position to a third position in response to movement of said back-rest from said corresponding second position to a corresponding third position, and means for preventing

operation of said actuating means during movement of said seat and back-rest from their respective first positions to their respective second positions, and to release said actuating means for operation in said second positions of said seat and back-rest to then permit said back and said seat to move from the second position to said third position and to prevent movement of said back and seat from the first to the third position without passing through said second position.

2. A reclining chair, comprising support means, a separate and movable back-rest and a separate and movable seat, operating means pivotally connected to said support means and interconnecting said back-rest and said seat, for moving the latter from a first position to a second position in response to movement of said back-rest from a corresponding first position to a corresponding second position, actuating means operatively connected to said operating means for moving said seat from said second position to a third position in response to movement of said back-rest from said corresponding second position to a corresponding third position, and means for preventing operation of said actuating means during movement of said seat and back-rest from their respective first positions to their respective second positions, said last mentioned means comprising a sequence member mounted for movement on said actuating means and having a stop surface, a stationary stop member mounted on said support means and engaging said surface, spring means engaging said sequence member and biasing it in a direction so that said stop surface is in engagement with said stop member during the movement of said back-rest and seat from their respective first positions to their respective second positions, whereby said actuating means is prevented from moving during said last mentioned movement of said back-rest and seat, and means controlled by said operating means, when said operating means is in said second position, for moving said sequence member against said biasing means, in an opposite direction, to disengage said stop surface from said stop member and to permit movement of said actuating means.

3. A reclining chair, comprising support means, a separate and movable back-rest and a separate and movable seat, operating means pivotally connected to said support means and interconnecting said back-rest and said seat, for moving the latter from a first position to a second position in response to movement of said back-rest from a corresponding first position to a corresponding second position, actuating means operatively connected to said operating means for moving said seat from said second position to a third position in response to movement of said backrest from said corresponding second position to a corresponding third position, means for preventing operation of said actuating means during movement of said seat and back-rest from their respective first positions toward their respective second positions, and to release said actuating means in said second positions of said seat and back-rest, said operating means having a member thereon for engaging a part of said actuating means in said second respective positions of said back-rest and seat, releasable stop means for engaging a part of said actuating means in the position thereof corresponding to said respective third positions of said back-rest and seat for releasably holding said back-rest and seat in said respective third positions thereof, and stationary stop means in position for engaging said actuating means in another position thereof corresponding to respective fourth positions of said back-rest and seat in response to additional movement of said back-rest in the same direction as movement thereof from said corresponding second position to said corresponding third position.

4. Operating mechanism for a chair having a support, a back-rest and a seat, said mechanism comprising support means adapted to be mounted on said support, a first member adapted to be fixedly connected to said

back-rest, a second member adapted to be fixedly connected to said seat and pivotally connected to said first member, a third member pivotally connected to said first member and to said support means, movable pivot means operatively connected to said support means, a fourth member pivotally connected to said second member and to said pivot means, and means mounted on said support means for preventing movement of said pivot means during movement of said first member from a first position toward a second position while said second member concurrently moves from a corresponding first position toward a corresponding second position, and to release said pivot means in said second positions of said back-rest and seat.

5. Operating mechanism for a chair having a support, a back-rest and a seat, said mechanism comprising support means adapted to be mounted on said support, first operating linkage means pivotally connected to said support means and adapted to be operatively connected to said back-rest and said seat, second operating linkage means pivotally mounted on said support means and operatively connected to said first linkage means for operation in response to the operation of said first linkage means, said second linkage means including a first link pivotally connected to said first linkage means, said first linkage means having a part for engaging said first link as said first linkage means moves from a first position into a second position for operating said first link and thereby operating said second linkage means, said second linkage means including a movable sequence member, stop means engaging said sequence member during said movement of said first linkage means from said first position to said second position so that said second linkage means is rendered inoperable during said movement, said sequence member having means thereon positioned in the path of movement of said first link for moving said sequence member away from said stop means when said first link is in a position corresponding to said second position of said first linkage means, whereby said second linkage means is free to move upon further movement of said first linkage means.

6. In combination, support means, chair back means movably connected to said support means, chair seat means movably connected to said chair back means, a member pivoted to said support means, a link pivoted to said pivoted member and also pivoted to said chair seat means, a sequence member pivoted to said pivoted member, stop means on said support means, engaging said sequence member and preventing pivotal movement of said pivoted member in one direction while said stop means is in engagement with said sequence member, and engaging means on said sequence member adapted to be engaged by said link, to move said sequence member out of engagement with respect to said stop means, said link being spaced from said engaging means, and said stop means being in engagement with said sequence member while said chair back means and said chair seat means move from a first toward a second position thereof, and said link contacting said engaging means and moving said sequence member to release position, out of engagement with respect to said stop means, toward the end of the movement of said chair back means and chair seat means, to said second positions thereof, to release said pivoted member, and allow pivotal movement of said pivoted member in said direction upon moving said chair back means and chair seat means to a third position thereof.

7. The combination of claim 6, and means on said chair seat means adapted to engage said link upon said link moving said sequence member to release position, whereby said chair seat means and said link move together in fixed relative positions, as said pivoted member pivotally moves in said direction, after release of said sequence member, and said chair seat means and chair back means move from the second positions thereof to said third positions thereof.

8. The combination of claim 6, and stop means to retain said pivoted member against further pivotal movement in the third positions of said chair seat means and chair back means.

9. The combination of claim 8, said last mentioned stop means being releasable, and spring means acting to prevent release of said last mentioned stop means, upon moving said chair back means and chair seat means from third positions thereof to fourth positions thereof and applying additional rotative force on said pivoted member to overcome said spring means.

10. In combination, a chair back member, a chair seat member, a support means, means to movably connect said chair back member and said chair seat member to each other and to said support means, for movement of said chair back member and chair seat member, relative to each other and relative to said support means, from first to second positions of said chair back member and chair seat member relative to each other and relative to said support means, a member movably mounted on said support means, means controlled by said movably mounted member to move said second member, a sequence member mounted on said movably mounted member, stop means on said support means engaging said sequence member, in the first positions of said chair back member and chair seat member, to prevent movement of said movably mounted member relative to said support means, and means controlled by movement of said second member, to move said sequence member out of engagement with respect to said stop means, upon moving said first two members, into said second positions thereof, to thereby release said movably mounted member and permit movement thereof, to control movement of said second member upon moving said first two members from said second positions to third positions thereof relative to each other and to said support means.

11. The combination of claim 10, and means to hold one of said first two members, against movement relative to said controlled means, in said second positions of said chair back and chair seat members, allowing said first two members to move to said third positions, with said one of said first two members and said controlled means retaining their positions relative to each other.

12. In combination, a first member adapted to be attached to a chair back, a second member adapted to be attached to a chair seat and being pivoted at its rear end to said first member, a fixed support, a first link pivoted to said fixed support and pivoted to said first member, means movably mounted on said fixed support and carrying a pair of front and rear movable pivots, a pair of links each pivoted to one of said pair of movable pivots, said pair of links being pivoted to said second member, releasable means to prevent movement of said pair of movable pivots during a first movement of said first two members from initial positions to second positions, during which movement, said first link and said pair of links rotate rearwardly, and said first and second members move rearwardly, means controlled by movement of said first and second members as the end of said first movement to release said preventing means, to allow movement of said movably mounted means to raise said pair of movable pivots, as said first and second member move through a second movement from said second positions thereof to third positions thereof and means to stop movement of said first and second members in said third positions.

13. The combination of claim 12, said last means being releasable by force applied to one of said members, to allow movement of said first and second members through a third movement from said third positions to a fourth position of said first and second members, and fixed means to stop movement of said first and second member in said fourth positions.

14. The combination of claim 13, and means to prevent angular movement of said second member relative to said rear link during said second and third movements.

15. In combination, a support means, a body supporting member, means including a first link to connect said body supporting member to said support means, a first lever pivoted to said support means and having a pair of arms, means including a second link connecting one arm of said first lever to said body supporting means, a second lever pivoted to said support means and having a pair of arms, means to connect the other arm of said first lever to one of said arms of the second lever, a control member pivoted to the other arm of said second lever and also pivoted to said body supporting member, a leg-rest member, lazy tong means connecting said leg-rest member to said body supporting member and comprising a plurality of interpivoted elements, and means to move said lazy-tong means to project and retract the leg-rest member, including a link connecting said control member to an element of said lazy-tong means, and means to lock the first lever against pivotal movement, in the retracted position of said leg-rest member, and to release said last means in the projected position of said leg-rest.

16. In combination, a support means, a body supporting means, a first link means to movably connect said body supporting means to said support means, a first member pivoted to said support means, a second member pivoted to said support means, a second link means interconnecting said first and second pivoted members, a third link means connecting said first pivoted member to said body supporting means, a fourth link means connecting said second pivoted member to said body supporting means, said body supporting means being movable from a first position to a second position, causing movement of said first link means and fourth link means, means to prevent movement of said first pivoted member from a first position thereof, during said movement of said body supporting means from its first position toward its second position, whereby to prevent movement of said second pivoted member during such movement, and to release said first pivoted member for movement in one direction when said body supporting means is in its second position, whereby said body supporting means may move from its second position to a third position accompanied by movement of said first and second pivoted members.

17. The combination of claim 16, a leg-rest, and means controlled by said fourth link means to cause projection of said leg-rest as said body supporting means moves from its first to its second position.

18. The combination of claim 16, said body supporting means comprising a seat member adapted to be attached to a chair seat, and said first link means comprising a back-rest member pivoted to the seat member and adapted to be attached to a back-rest of the chair, and a link pivoted to said back-rest member and to said support means.

19. The combination of claim 16, in combination with stop means on said support means to stop rotation of said first member in an opposite direction from its first position.

20. In combination, a support means, a first link pivoted thereto, a first member adapted to be attached to a chair back, pivoted to said first link, a second member adapted to be attached to a chair seat, pivoted to said first member, a first lever pivoted to said support means, a second link pivoted to said first lever and also pivoted to said second member, a second lever pivoted to said support means, a third link pivotally connected to said first lever and pivotally connected to said second lever, a third member pivoted to said second lever and also pivoted to said second member, releasable means to hold said first lever against rotation, during a first phase of movement of said first and second members and means on said second link to release said hold means toward the end of said first phase of movement to permit movement of said first lever during a second phase of movement of said first and second members.
